(57) **CLAIM**

The ornamental design for a target device for merchandiser, as shown and described.

DESCRIPTION

FIG. 1 is a perspective view of a target device for merchandiser, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a view showing an example of the usage of the target device for merchandiser.

In the drawings, the broken line showing of a mechanical elements on the rear of the design depicts environmental subject matter and forms no part of the claim.
